CLAIM

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of a first embodiment of a display screen or portion thereof with animated graphical user interface;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a front view of a first image of a second embodiment of a display screen or portion thereof with animated graphical user interface;

FIG. 10 is a second image thereof;

FIG. 11 is a third image thereof;

FIG. 12 is a fourth image thereof;

FIG. 13 is a fifth image thereof;

FIG. 14 is a sixth image thereof;

FIG. 15 is a seventh image thereof; and,

FIG. 16 is an eighth image thereof.

The uneven-length broken lines immediately adjacent to the claimed area depict boundaries of the claimed design and form no part thereof. The even-length broken lines showing the remainder of the display screen or portion thereof with animated graphical user interface depict environmental
